P. H. J. COVERDALE

CURING RACK

Filed Dec. 2, 1921

FIG. 2.

FIG. 3.

FIG. 4.

UNITED STATES PATENT OFFICE.

PHILIP H. J. COVERDALE, OF BEAUMONT, TEXAS.

CURING RACK.

Application filed December 2, 1921. Serial No. 519,423.

To all whom it may concern:

Be it known that I, PHILIP H. J. COVERDALE, a citizen of the United States, residing at Beaumont, in the county of Jefferson 5 and State of Texas, have invented certain new and useful Improvements in Curing Racks, of which the following is a specification.

This invention relates to supports or racks 10 for supporting rice in the field after it has been cut, in order to dry it or cure it to the best advantage, and which may be used for other similar crops. This invention consists in the novel construction and combination 15 of the parts hereinafter fully described and claimed whereby the rice is supported clear of the ground.

In the drawings, Figure 1 is an end view of a rack constructed according to this invention. Fig. 2 is a side view of the same. Fig. 3 is a side view of two panels which form the curing rack, arranged flat for shipment. Fig. 4 is an end view of the same.

Two panels 5 and 6 are provided. The 25 panel 5 is formed of uprights 7 and longitudinal bars 8 and 8'. The top and bottom bars are arranged parallel to each other and have their backs against the fronts of the uprights. The middle longitudinal bar 8' 30 may also be parallel to the bars 8, but it is preferably arranged at an angle to them and diagonally of the panel, in order to stiffen the panel. The uprights and longitudinal bars are preferably relatively broad 35 in proportion to their thickness, as this construction gives the panels liberal outer surfaces for the rice straw to rest against, when the panels are arranged as shown in Figs. 1 and 2.

The panel 6 is formed of uprights 9 and longitudinal bars 10 and 10', which are similar to the uprights 7 and longitudinal bars 8 and 8'. The uprights 9 however are spaced wider apart than the uprights 7 so that their 45 end portions will straddle the end portions of the uprights 7 when the panels are set up at an angle to each other as shown in Fig. 1.

The middle bar 10' is also inclined in the 50 opposite direction to the middle bar 8', so that the bars 10' and 8' extend crosswise of each other. The uprights of each panel are also preferably arranged at an acute angle to each other, as this gives the rack a broad-

er base and enables it to stand wind pressure better. 55

The two panels have no pivot pins for connecting them together. The back of each of the uprights 7 and 9 bears pivotally against one sharp corner of one of the longitudinal bars, so that the panels can be moved pivotally of each other, and can be set up at various angles without having any pivot pin connections. When not in use the panels are piled together in pairs, as shown 60 in Figs. 3 and 4, with the uprights of each pair of panels arranged side by side in the same plane.

When the two panels are arranged at an acute angle, as shown in Fig. 1, the weight 70 of the crop which is piled against their outer sides does not spread them apart. The uprights project above and below the top and bottom bars of the panels, and interlock at the meeting parts of the panels. 75

When the panels are set at an obtuse angle, which is sometimes desirable, a flexible connection 12 is secured between them, to prevent them from spreading. Two of these connections or cords 12 are preferably provided, and their ends are preferably secured to the projecting end portions of the uprights. The device can be inverted and used as a hay rack or fodder rack if desired, and the cords 12 are then necessary to prevent 80 its upper part from spreading as the hay is placed between the upper parts of the panels. 85

What I claim is:

1. A support or rack, comprising two similar panels formed wholly of longitudinal bars and uprights which have end portions which project crosswise of and beyond the longitudinal bars and which are spaced wider apart in one panel than in the other, said bars and uprights being secured back to front and being relatively broad in proportion to their thickness, said panels being adapted to be stood loosely together at an angle to each other and with the backs of the uprights of each panel bearing pivotally against one corner of the adjacent longitudinal bar of the other panel and thereby holding the panels in position so that they will support a load. 90

2. A support or rack, comprising two similar panels formed wholly of longitudinal bars and uprights which have end portions which project crosswise of and beyond 95 100 105

the longitudinal bars and which are spaced wider apart in one panel than in the other, said bars and uprights being secured back to front and being relatively broad in proportion to their thickness, said panels being adapted to be stood loosely together at an angle to each other and with the backs of the uprights of each panel bearing pivotally against one corner of the adjacent longitudinal bar of the other panel and thereby holding the panels in position so that they will support a load, and flexible connections secured between the two panels and preventing them from spreading apart when arranged at an obtuse angle or when inverted.

3. A rack, comprising two similar panels formed wholly of longitudinal bars and uprights, secured back to front, the said uprights being arranged at an angle to each other and spaced wider apart in one panel than in the other, said panels being adapted to be stood loosely together at an angle to each other with their uprights crossing each other and with the backs of the uprights of each panel bearing pivotally against one corner of the adjacent longitudinal bar of the other panel.

4. A rack, comprising two similar panels formed wholly of longitudinal bars and uprights, secured back to front, the upper and lower longitudinal bars of each panel being arranged parallel to each other and the intermediate longitudinal bar being arranged diagonally and at an angle to them, said panels being adapted to be stood loosely together at an angle to each other with their uprights crossing each other and with the backs of the uprights of each panel bearing pivotally against one corner of the adjacent longitudinal bar of the other panel.

backs of the uprights of each panel bearing pivotally against one corner of the adjacent longitudinal bar of the other panel.

5. A rack, comprising two similar panels formed wholly of longitudinal bars and uprights, secured back to front, the upper and lower longitudinal bars of each panel being arranged parallel to each other and the intermediate longitudinal bar being arranged diagonally and at an angle to them, said panels being adapted to be folded closely together for shipment with their uprights arranged side by side in the same plane, said panels being adapted to be stood loosely together at an angle to each other, so as to support a load, with their uprights crossing each other and with the backs of the uprights of each panel bearing pivotally against one corner of the adjacent longitudinal bar of the other panel.

6. A rack, comprising two similar panels formed wholly of longitudinal bars and uprights, secured back to front, the said uprights being arranged at an angle to each other and spaced wider apart in one panel than in the other, said panels being adapted to be folded closely together for shipment with their uprights arranged side by side in the same plane, said panels being adapted to be stood loosely together at an angle to each other, so as to support a load, with their uprights crossing each other and with the backs of the uprights of each panel bearing pivotally against one corner of the adjacent longitudinal bar of the other panel.

In testimony whereof I have affixed my signature.

PHILIP H. J. COVERDALE.
